METHOD OF WEAVING FRIEZE PILE
FABRICSAlbert W. Drobile, Wayne, Pa., assignor to Collins
& Aikman Corporation, Philadelphia, Pa., a
corporation of Delaware

Application March 14, 1935, Serial No. 10,978

4 Claims. (Cl. 139—21)

My invention is a method of simultaneously weaving in superposed relation a plurality of frieze pile fabrics having self-separating loops of different lengths woven face to face on a double shuttle loom having a pair of sets of shedded pile gauges extending warpwise.

In accordance with my invention, the shuttles of a double shuttle loom are picked simultaneously to lay complementary pairs of weft threads, and the sets of gauges, and the warp threads are so shedded that the picks laid by the upper shuttle form a row of wefts above the top set of gauges and a row of wefts between the gauges and the picks laid by the bottom shuttle form a row of wefts between the gauges and a row of wefts below the bottom gauges, the gauges being shedded together or toward one another when the wefts are being laid above and below the gauges and the sets of gauges being shedded apart when the rows of wefts are being laid between the gauges. The sets of gauges operate on the mid-closing principle, that is they have two positions, a horizontal position and a deflected position. The upper set of gauges is moved upwardly and the lower set downwardly from their horizontal positions. The warp threads are so shedded during the laying of the picks that most of the wefts in the row above the gauges are interlaced with the ground warp threads to form the ground of the upper fabric and to secure in such ground pile warp threads looped over the upper row of wefts between the gauges to form short loops on the upper fabric, and to also secure to the upper ground pile warp threads which are looped over certain of the wefts between the lower gauges and the lower ground to form long pile loops on the upper ground. Similarly, ground warps interlace the wefts below the gauges, excepting those looped within long loops of the upper fabric, to form the ground of the lower fabric and secure thereto pile warp threads looped over the remaining or lower wefts between the gauges and also secured to the lower ground the long loops formed by pile warp threads passing over the wefts above the top gauges which are not interlaced with the upper ground.

Preferably the rows of loops of different heights on each fabric adjoin one another in regular repeat or in pattern formation and the pile loops may be united with the ground in a loose pile of V-tuft construction, or the pile loops may be united with the ground in a tight pile of W-tuft construction. Where the W-tuft construction is used, the intermediate portion or knee of the W-tuft may pass over one ground weft only or

may pass over two or more ground wefts. In any of these types of construction, the ground may be composed of two series of tight warp threads with uniform take-up or may be composed of one series of tight warps and one series of slack warps so as to vary the appearance and erectness of the pile loops. The low loops and high loops on each fabric may be formed from the same series of pile warp threads or may be formed from two different series of pile warp threads, one forming the low loops and the other forming the high loops, which may be led off by two delivery mechanisms.

Fabrics having a surface pattern or figure composed of high and low loops according to a pre-arranged design may be woven in accordance with my method by so shedding the pile warps that a high pile loop or a low pile loop, or both of them, can be formed on any ground weft or wefts, as required or desired for the production of the desired design or figure.

During the weaving of the fabrics and at the fell of the cloths where the wefts are beaten up, the two fabrics are interlocked due to the interlacing of the pile yarns therefor over and between the two sets of shedded warpwise gauges, which act as retaining or coupling pins and coact with the let-off mechanism to regulate the length of the long pile loops. After the fabrics move down toward the take-off rollers, the wefts slide off of the ends of the gauges to permit the self-separating of the loops and the separation of the fabrics by merely cutting the few connecting threads at the selvages.

The characteristic features and advantages of my improvements will further appear from the following description and the accompanying drawings in illustration thereof.

In the drawings, Fig. 1 is a diagrammatic fragmentary view illustrating the weaving of superposed pile fabrics in accordance with my invention and the separation of the pile loops thereof as they move down off the ends of the warpwise extending gauges; Fig. 2 is a diagrammatic fragmentary view illustrating the weaving of superposed pile fabrics in modified form in accordance with my invention and the separation of the pile loops thereof as they move down off the ends of the warpwise extending gauges; Fig. 3 is a fragmentary diagrammatic view illustrating the weaving of superposed pile fabrics of a further modified form in accordance with my invention and the separation of the pile loops thereof as they move down off the ends of the warpwise extending gauges; Fig. 4 is a diagrammatic frag-

mentary view illustrating the weaving of superposed pile fabrics with tight and slack ground warp threads in accordance with my invention and the separation of the pile loops thereof as 5 they move down off the ends of the warpwise extending gauges; Fig. 5 is a diagrammatic fragmentary view illustrating the weaving of superposed fabrics with high and low loops over the same ground weft; Fig. 6 is a fragmentary dia- 10 grammatic view illustrating the fabric woven in accordance with Fig. 5 after the removal of the pile supporting wefts; Fig. 7 is a "drawing-in" diagram for drawing in the warps for weaving the fabric illustrated in Fig. 5, and Fig. 8 is a dia- 15 gram illustrating the shedding of the warps during the weaving of a repeat of the fabric illustrated in Fig. 5.

In the practice of my invention as illustrated in Fig. 1, a double shuttle loom having the simultaneously operable shuttles X and X' and a usual reed Y is provided with warpwise extending gauge wires A, A' which may have their rear ends connected with a cross-bar Z.

The gauges A and A' preferably consist of round resilient wires which pass through and are shedded by heddles in suitable heddle frames (not shown) and pass through the reed spaces between the reed dents and slightly past the fell of the fabric being woven.

30 The loom is also provided with suitable heddle frames and harness mechanism for shedding in desired sequence the pile warp P¹ and the ground warps B¹ and B² for forming the upper fabric and the pile warp P² and the ground warps B³ and B⁴ for forming the bottom fabric.

The cycle of weaving a repeat of the fabric may be considered as starting with the simultaneous laying of the wefts 1a and 1b which are laid by the shuttles X and X' respectively above 40 the set of gauges A and below the set of gauges A' while the gauges are both shedded toward one another by the heddle and harness mechanism of the loom. The weft 1a is laid between the ground warp threads B² and the ground warp threads B¹ and the pile warp threads P¹ and forms a ground weft in the upper fabric and secures thereto the pile warp threads P¹. The weft 1b is laid between the ground warp threads B³ and the ground warp threads B⁴ and pile 45 warp threads P² and forms a ground weft in the lower fabric and secures therein the pile warp threads P².

After the beating up of the wefts 1a and 1b by the lay and the crossing of the respective pairs 50 of ground warp threads, the shuttles X and X' lay the respective wefts 2a and 2b between the gauges A, A' while the gauges are shedded apart by a heddle and harness mechanism to permit the passage of the shuttles. During the laying 55 of the picks 2a and 2b the pile warp threads P¹ and the pile warp threads P² are shedded to the middle pile position and the ground warp threads of the upper fabric are shedded above the shuttle X and the ground warp threads of the upper fabric are shedded above the shuttle 60 X and the ground warp threads of the lower fabric are shedded below the shuttle X'. Consequently, on the next shedding of the pile warp threads P¹ and P², the weft 2a is drawn against the gauges A and a short loop is formed on the upper fabric and the weft 2b is drawn against the gauges A' and a short loop is formed on the bottom fabric.

Before the pile warps P¹ and P² are shedded, 75 however, to form the short loops, the gauges A, A'

are shedded toward one another to permit the laying of the weft 3a by the shuttle X above the gauges A and to permit the laying of the weft 3b by the shuttle X' below the gauges A'. The weft 3a is laid between the appropriately shedded ground warp threads B¹ and B² to form merely a ground weft in the upper fabric. The weft 3b is laid between the appropriately shedded ground warp threads B³ and B⁴ and forms merely a ground weft in the lower fabric. The normal 10 operation of the loom will beat up the wefts 3a, 3b, into substantial vertical alignment with 2a, 2b respectively.

While the gauges A and A' are still shedded toward one another the shuttle X lays a further 15 weft 4a above the gauges A and the shuttle X' lays a further weft 4b below the gauges A'. During the laying of the weft 4a the ground warp threads B¹ and the pile warp threads P¹ are shedded in the upper positions in the upper shed 20 and the ground warp thread B² is shedded in the lower position of the upper shed. Consequently the weft 4a forms a ground weft in the upper fabric and secures therein the pile warp P¹ to complete the formation of the short loops over 25 the weft 2a. During the laying of the weft 4b the ground warp threads B³ are shedded in the upper position of the bottom shed and the ground warp threads B⁴ and pile warp threads P² are shedded in the lower positions in the bottom shed 30 so that the weft 4b forms a ground weft in the bottom fabric and secures therein the pile warp threads P² to complete the formation of short loops over the weft 2b.

During the laying of the wefts 5a and 5b by 35 the shuttles X and X', the set of gauges A are in their middle position so that the weft 5a is laid above such gauges and between the ground warp threads B¹ and B² to form a ground weft in the upper fabric. The set of gauges A', however, are shedded to their upper or horizontal position so that the weft 5b is laid below the gauges A' but above the plane of the warps of the bottom shed and above the pile warp threads P¹ which are shedded to their lowermost position. Consequently the weft 5b is not engaged 45 in the bottom ground but is drawn against the gauges A' to form a support for a row of long loops on the top fabric.

During the laying of the wefts 6a and 6b respectively by the shuttles X and X', the set of gauges A is shedded downwardly to a lower or horizontal position and the warps of the upper fabric and the pile warp threads P² of the lower fabric are all shedded to an upper position so 55 that the weft 6a is not engaged with the warps of the upper fabric but lie beneath the pile warp threads P² of the lower fabric and is drawn thereby against the gauges A to form a long loop on the lower fabric. The set of gauges A' is shedded 60 to its middle position so that the weft 6b is laid beneath the same and within the shed formed by the spaced warp threads B³ and B⁴ and forms a ground weft in the lower fabric.

By the continued repetition of the foregoing 65 cycle, there are produced upper and lower fabrics each having loops of unequal length which slide off the ends of the gauges A, A' and permit the self-separation of the fabrics. Such fabrics may be expeditiously woven and have well covered grounds since there is a loop supported by 70 a supplementary weft over every other ground weft of the fabric.

When it is desired to interlace the pile warps in the ground with a W interlacing, instead of 75

the V interlacing shown in Fig. 1, this may be done as illustrated in Fig. 2 by providing one set of warp ends for each fabric to form the short loops thereon and a second set of warp ends for each fabric to form the long loops thereon.

In weaving such a fabric, as illustrated in Fig. 2, the picks 1a, 1b, 2a, 2b, 3a, 3b, 4a, 4b, 5a, 5b, 6a and 6b are laid in the same way as in Fig. 1 and the ground warps B¹, B², B³ and B⁴ are interlaced with the ground wefts in the same way as in Fig. 1. The pile warp ends P¹⁰ and P²⁰ are shedded to form short loops over the wefts 2a and 2b of the upper and lower fabrics respectively, but instead of the pile warp ends P¹⁰ being looped over the wefts 5b, such ends are drawn into the upper ground and interlaced tightly therein over the ground weft 5a. Similarly the pile warp ends P²⁰, instead of being looped over the supplementary weft 6a, are interlaced tightly in the ground and over the ground wefts 6b. Additional sets of pile warp ends P¹¹ and P²¹ are provided to form long loops respectively on the upper and lower fabric. The pile warp ends P¹¹ are first interlaced with a W interlacing around the wefts 1a, 3a and 4a and are then looped over the weft 5b between the gauges A' and the ground of the bottom fabric and then returned to the top fabric for a further W interlacing with the ground thereof. The pile warp ends P²¹ are first engaged by a W interlacing with the bottom fabric ground and are then looped over the weft 6a disposed between the gauges A and the ground of the upper fabric before being returned to the lower ground for a further W interlacing there- with.

When the fabric so woven is moved down off the ends of the gauges A and A', the fabrics automatically separate and there is thus provided two fabrics each having alternating rows of short pile loops and long pile loops spaced from one another by but a single ground weft and with both the long pile loops and the short pile loops held in the respective grounds by a W-type interlacing.

Where close coverage of the ground by the loops is not requisite, the intermediate portions of the W interlacing in the ground of the pile warps may be floated over a plurality of ground wefts, as shown in Fig. 3, instead of over a single ground weft as shown in Fig. 2. With this type of construction, as shown in Fig. 3, additional wefts 7a and 8a are inserted in the top fabric on opposite sides of the weft 5a and additional wefts 7b and 8b are inserted in the ground of the bottom fabric on the opposite sides of the weft 6b. Pile warps P¹⁰⁰, forming the short loops on the upper fabric, are interlaced in the ground thereof over the weft 4a, under the wefts 1a, 5a, and 8a, and over the weft 1a before being looped over the weft 2a. Similarly the pile warp ends P²⁰⁰, forming the short pile loops on the lower fabric, are interlaced in the ground thereof under the weft 4b, over the wefts 1b, 6b, 8b and under the weft 1b before being looped over the weft 2b thereof. The pile warp ends P¹¹¹, forming on the upper fabric loops supported by the supplementary wefts 5b, are interlaced in the ground thereof over the weft 8a, under the wefts 1a, 3a and 4a and over the weft 1a. The pile warp ends P²¹¹, forming on the lower ground the long pile loops supported by the supplementary wefts 6a, are interlaced in the lower ground under the wefts 8a, over the wefts 1b, 3b, 4b and under the weft 1b.

Instead of the ground warps B¹, B², B³ and B⁴ being under equal tension, as in Figs. 1, 2 and 3,

one of the ground warps in the upper ground may be placed under tight tension and the other ground warp in the upper ground may be placed under slack tension. Similarly one of the ground warps in the lower ground may be placed under tight tension and the other ground warp in the lower ground placed under slack tension. The application of tight and slack tensions to the respective ground warps of the weave shown in Fig. 3 is illustrated in Fig. 4 where the ground warps B¹ and B³ are under tight tension and the ground warps B² and B⁴ are under slack tension, thereby shifting the rows of loops closer toward one another.

As illustrated in Figs. 5 to 8 inclusive, fabrics may be woven face to face in accordance with my invention with a long loop or a short loop or both over any particular ground weft or wefts of each fabric. In accordance with this modification, a repeat having the foregoing characteristics consists of two ground wefts and two pile supporting wefts and two ground warps and two pile warps in each fabric. The first pair of wefts 1a and 1b are simultaneously laid by the shuttles of a double shuttle loom respectively above the gauge A and below the gauge A'. The weft 1a is laid in a shed formed by the backing warp threads B¹, B², and under the pile warps P¹⁰⁰¹ and P¹⁰⁰². The weft 1b is laid in a shed formed by the ground warp threads B³ and B⁴ and above the pile warps P¹⁰⁰³ and P¹⁰⁰⁴.

Before the laying of the next pair of wefts 2a and 2b, the sheds are changed as shown in Fig. 7 by shedding the warps so that the weft 2a is laid in the top ground formed by the ground warps B¹, B² and above both pile warps P¹⁰⁰¹ and P¹⁰⁰². The weft 2b is laid above the bottom fabric and beneath the pile warp P¹⁰⁰¹ and the gauge A'. The backing warps and gauges have only two weaving positions.

Before the laying of the next pair of wefts 3a and 3b, the gauges A and A' are shedded so that the weft 3a is laid between the gauges A and the pile warp P¹⁰⁰², and the weft 3b is laid between the gauges A' and the pile warp P¹⁰⁰³.

Before the laying of the next pair of wefts 4a and 4b, the gauges and warps are again shedded so that the weft 4a is laid below the top fabric and between the gauge A and the warp threads P¹⁰⁰⁴ and the weft 4b is laid in the ground formed by the ground warps B³ and B⁴ and beneath both the pile warps P¹⁰⁰³ and P¹⁰⁰⁴. As the fabric weaves down toward the take-up rolls, the loops slide off the end of the gauges A and A' to permit the fabrics to separate from one another, and when the pile supporting wefts are pulled, a high loop and a low loop are left over a ground weft in each repeat.

Should it be desired to form a cut and uncut looped fabric from any of the looped fabrics above described, the tops of the long loops may be sheared off to form cut pile tufts substantially equal to or greater than the height of the uncut short pile loops.

Having described my invention I claim:

1. In the simultaneous manufacture of a plurality of frieze pile fabrics having long and short loops on a double shuttle loom having a pair of sets of shedded pile gauges extending warpwise of the loom, the steps which comprise shedding the sets of gauges together and simultaneously laying picks outside the gauges forming ground wefts in the respective fabrics, shedding the sets of gauges apart and laying simultaneously picks between the wefts forming face wefts for sup-

- porting free short loops on the respective fabrics, looping pile warp threads secured to the respective grounds over the respective wefts between the gauges, shedding the gauges together and laying 5 simultaneously a pair of picks outside the gauges, one of which forms a ground weft in one of the fabrics and the other of which is laid between the gauges and a ground of the other fabric to form a face weft for a free long pile loop on one of 10 the fabrics in which the complementary pick forms a ground weft looping a warp thread from the fabric more removed therefrom about said face weft and securing said pile warp into the fabric of its origin.
- 15 2. In the manufacture simultaneously of a plurality of frieze pile fabrics having superposed grounds on a double shuttle loom having a plurality of gauges extending warpwise of the loom, the steps which include laying a row of weft 20 above the gauges and a row of wefts below the gauges, and two rows of wefts between the gauges, interlacing ground warps with some but not all of the row of wefts above the gauges, interlacing ground warps with some but not all 25 of the row of wefts below the gauges, looping warp threads secured to the upper ground over some of the wefts between the gauges and over the remaining wefts below the gauges which are not interlaced with the bottom ground warps and 30 looping pile warp threads secured to the bottom ground over some of the wefts between the gauges and over the remaining wefts above the gauges which are not interlaced with the top ground warps.
- 35 3. In the manufacture simultaneously of two frieze pile fabrics face to face on a double shuttle loom having two sets of superposed shedded gauges between the grounds of the fabrics and extending warpwise of the loom, the steps which 40 include setting both gauges to their horizontal positions, shedding the ground warps and pile warps and simultaneously inserting wefts in the sheds formed thereby so that the pile warps lie at the back of their respective fabrics, then closing the sheds and beating up the wefts into position, forming a second set of sheds and simultaneously inserting wefts so that some of the pile threads of one of the fabrics are supported by a weft over the gauges more remote from the back of such fabric and the other weft is inserted in the ground of the same fabric to which the said pile is bound, closing the sheds and beating up the second set of wefts into position, forming a third shed and moving the gauges 10 in opposite directions from each other, simultaneously inserting a third set of wefts between the gauges so as to act as a support for other pile warps from both fabrics, closing such shed and 15 beating up the third set of wefts into position, forming a fourth shed and returning the gauges to their horizontal position, then simultaneously inserting a set of wefts so that the remaining pile threads are supported only by a weft over the 20 gauges more remote from the back of the fabric to which the pile threads are bound, the other weft being inserted in the ground of said fabric, closing the shed, and beating up the fourth set of wefts preparatory to repeating the cycle. 25
4. In the simultaneous manufacture of self-separating frieze fabrics having pile loops of two different heights face to face on a double shuttle loom having two sets of shedable warpwise extending gauges spaced between the grounds of 30 the two fabrics, the steps which comprise positioning the sets of gauges in substantially parallel relation, maintaining a portion of each of the gauges in such position during weaving by the supporting wefts of the long and short loops 35 of opposite fabrics, shedding the gauges away from their parallel position and laying the short loop supporting wefts between the gauges, returning the gauges to their parallel positions and laying the long loop supporting wefts outside the 40 gauges and free from the ground warps between the selvages.

ALBERT W. DROBILE.
